(57) **CLAIM**

The ornamental design for a case for location tracker as shown and described.

DESCRIPTION

FIG. 1 is a front side perspective view of a case for location tracker, showing my new design;

FIG. 2 is a front view of the case for location tracker of FIG. 1;

FIG. 3 is a back view the case for location tracker of FIG. 1;

FIG. 4 is a first side view the case for location tracker of FIG. 1;

FIG. 5 is a second side view the case for location tracker of FIG. 1;

FIG. 6 is a third sideview the case for location tracker of FIG. 1; and,

FIG. 7 is a fourth side view the case for location tracker of FIG. 1.

The broken lines are for illustrating portions of the case for location tracker which form no part of the claimed design.
